HOME AIR PURIFIER

Max D. Peters, 633 Turnpike Road,
Minneapolis, Minn. 55416

Filed Oct. 13, 1971, Ser. No. 189,077

Term of patent 14 years

Int. Cl. D23—99

U.S. Cl. D23—149

FIG. 1.

FIG. 2.

FIG. 3.

FIG. 4.

FIG. 5.

FIG. 6.

FIG. 7.

FIG. 8.

FIG. 9.

FIG. 1 is a top plan view of a home air purifier showing my new design;

FIG. 2 is a side elevational view thereof, all sides being identical excluding the knob;

FIG. 3 is a bottom plan view thereof;

FIG. 4 is a top plan view of a second embodiment of my new design;

FIG. 5 is a side elevational view thereof, the opposite side being identical excluding the knob;

FIG. 6 is a bottom plan view thereof;

FIG. 7 is a top plan view of a third embodiment of my new design;

FIG. 8 is a side elevational view thereof, all sides being identical excluding the knob; and

FIG. 9 is a bottom plan view thereof.

The mesh is partially shown on the sides and bottom for convenience of illustration, it being understood that the mesh is continuous over the areas indicated.

I claim:

The ornamental design for a home air purifier, as shown and described.
